US00D779541S

(12) **United States Design Patent** (10) **Patent No.:** **US D779,541 S**
Cole (45) **Date of Patent:** **** Feb. 21, 2017**

(54) **DISPLAY SCREEN OR PORTION THEREOF OF A DEVICE WITH GRAPHICAL USER INTERFACE FOR A WELDING SYSTEM**

(71) Applicant: **Lincoln Global, Inc.**, City of Industry, CA (US)

(72) Inventor: **Stephen R. Cole**, Chula Vista, CA (US)

(73) Assignee: **Lincoln Global, Inc.**, City of Industry, CA (US)

(**) Term: **15 Years**

(21) Appl. No.: **29/569,743**

(22) Filed: **Jun. 30, 2016**

Related U.S. Application Data

(63) Continuation of application No. 29/472,473, filed on Nov. 12, 2013, now Pat. No. Des. 760,729.

CLAIM

The ornamental design for a display screen or portion thereof of a device with graphical user interface for a welding system, as shown and described.

DESCRIPTION

The FIGURE is a front view of a display screen or portion thereof of a device with graphical user interface for a welding system.

The outermost broken lines illustrate a display screen and form no part of the claimed design. The remaining broken lines illustrate portions of the graphical user interface and form no part of the claimed design.

1 Claim, 1 Drawing Sheet
